[57] CLAIM

I claim the ornamental design for a combined dispenser and cap, shown and described.

DESCRIPTION

FIG. 1 is an exploded front view of the combined dispenser and cap showing my new design;

FIG. 2 is a left side view thereof, the right side view being a mirror image thereof;

FIG. 3 is a rear view thereof;

FIG. 4 is a top view thereof;

FIG. 5 is a bottom view thereof; and,

FIG. 6 is a perspective top, left view thereof.
